UNITED STATES PATENT OFFICE.

ALFRED ROESCH, OF BROOKLYN, NEW YORK, ASSIGNOR OF TWO-THIRDS
TO WILLIAM B. WADSWORTH, OF PLAINFIELD, AND FREDERICK H.
DAVIS, OF ELIZABETH, NEW JERSEY.

AUTOMATIC HEAT-REGULATOR.

SPECIFICATION forming part of Letters Patent No. 583,632, dated June 1, 1897.

Application filed July 23, 1896. Serial No. 600,317. (No model.)

To all whom it may concern:

Be it known that I, ALFRED ROESCH, a citizen of the United States, residing at Brooklyn, in the county of Kings and State of New York, have invented new and useful Improvements in Automatic Heat - Regulators, of which the following is a specification.

My invention relates to improvements in air-controlling valve mechanism for that class 10 of heat-regulating systems in which compressed air is employed as the actuating power for opening and closing the steam-controlling valves and a thermostat is employed for operating the air-controlling valves.

15 The construction of my invention is explained by reference to the accompanying drawings.

Figure 1 illustrates a heat-regulating system with which my air-controlling valve 20 mechanism is adapted to be used. Fig. 2 is an enlarged view of the air-controlling valve mechanism shown in Fig. 1 in connection with the actuating-arm of a thermostat.

Like parts are referred to by the same reference-letters in both views.

That the object and function of my air-controlling mechanism may be more clearly understood, it is shown and described as arranged in connection with an air-reservoir 30 and a steam-radiator.

A represents the air-controlling mechanism proper, the function of which is to control the course of compressed air from the air-reservoir B both to and from the diaphragm-chamber C. The air-controlling mechanism A is actuated by the vibrating arm D of a thermostat, which arm is caused to move upward and downward as the temperature of the room is raised and lowered. When the arm D is 35 raised, air is permitted to pass from the air-reservoir B, through the air-controlling mechanism A, to the diaphragm-chamber C, and when said arm D moves downward the escape of air from the air-reservoir is cut off, when the air which has done its work in the diaphragm-chamber is permitted to pass back 40 to the air - controlling mechanism A, from which it escapes.

Steam is admitted from a steam-generator

to the steam-controlling valve E through the 50 pipe F, when it passes therefrom to the steam-radiator G through the steam-pipe H. The valve E is opened by the action of the spring I and closed by air-pressure upon the diaphragm J within the chamber C.

55

The passage of air from the air-reservoir to the diaphragm-chamber C is controlled by the valve K, which when in its normal condition closes the valve-seat L, but when said valve K is raised from its seat the compressed 60 air passes from the air-reservoir B, through the pipe M, to the inlet or primary air-chamber N, thence to the secondary or outlet chamber O, through the side duct P, thence to the diaphragm - chamber C, through the 65 pipe Q, when, acting through the diaphragm J, it closes said steam - controlling valve. When by a change of temperature of the room the actuating-arm D is moved downward, it first permits the valve K to close, when it 70 moves the valve R from its seat R', whereby the compressed air in the diaphragm-chamber C is permitted to escape, whereby the diaphragm J is raised by the action of the spring I and the steam-controlling valve E is 75 opened.

By a reverse movement of the arm D the valve R is first permitted to close, when the valve K is opened, as before described.

The arm D is connected at its free end with 80 the respective valve-stems S and T of the air-controlling valve through the branch arms u and y, which branch arms are formed with loosely-fitting recesses or apertures for the reception of said stems. The outer ends of 85 the stems S and T are each provided with bearing stops or nuts a a, against which the inner surfaces of said branch arms u and y are respectively brought to bear as said arm D is raised and lowered. Thus when the arm 90 D moves downwardly the branch u engages the bearing stop or nut a of the upper valve-stem, whereby the valve R is opened while the branch B moves freely over the lower valve-stem without communicating motion 95 thereto, while by a reverse movement of the arm D the branch arm u moves freely over the upper valve-stem without moving it, while

the lower branch γ engages the bearing stop or nut α of the lower valve-stem, whereby the lower valve K is opened.

- The valves K and R are preferably made 5 of soft rubber or other elastic substance, which will permit of enough compression to open the ports or valve-seats they respectively bear against, and which in their normal condition they are adapted to close, while they 10 at the same time react and bear against the inner walls of the respective chambers around the bearings of the respective valve-stems, and thus prevent the escape of air from such chambers around said valve-stems, whereby 15 the ordinary stuffing-boxes and packing usually employed around valve-stems are dispensed with.

It is obvious that by the peculiar construction and arrangement of the elastic air-controlling valves and the actuating branch arms connected with such valves one of said air-valves is always closed before the other is opened, whereby the loss of compressed air common with other forms of air-controlling 25 devices is avoided.

Having thus described my invention, what I claim as new, and desire to secure by Letters Patent, is--

1. In an air-controlling device for a heat-regulating system, the combination of a primary or inlet air-chamber provided with an inlet air-duct; an inlet air-controlling valve located in said primary air-chamber adapted to control the admission of air thereto; a secondary or outlet air-chamber; an air-duct 30 communicating between said primary and secondary air-chambers; an air-duct communicating from said secondary air-chamber

with a diaphragm-chamber of a steam-controlling valve; an air-controlling valve located 40 in said secondary air-chamber adapted to control the escape of air from said diaphragm-chamber; each of said air-controlling valves being provided with protruding valve-stems; a thermostatically-actuated arm communicating 45 with the protruding stems of said air-controlling valves, said thermostatically-actuated arm being adapted as it moves in either direction to engage the stems of and to actuate one of said air-controlling valves as 50 the other is automatically closed substantially as and for the purpose specified.

2. In an air-controlling device for a heat-regulating system the combination of a primary or inlet air-chamber provided with an 55 inlet air-duct; a secondary or outlet air-chamber provided with an air-duct communicating with the diaphragm-chamber of a steam-controlling valve; an air-duct communicating between said primary and secondary 60 air-chambers; two two-faced elastic air-controlling valves one located in each of said air-chambers and provided with protruding valve-stems one face of each of said two-faced elastic valves being adapted to close its seat 65 and the other face to close the space between said stems and their bearing-walls and means for actuating said air-controlling valve substantially as and for the purpose specified.

In testimony whereof I affix my signature 70 in the presence of two witnesses.

ALFRED ROESCH.
